UNITED STATES PATENT OFFICE.

CARADOC L. JONES, OF CHICAGO HEIGHTS, ILLINOIS.

COATING MACHINE.

Application filed April 14, 1925. Serial No. 23,107.

This invention relates to coating and more particularly to an apparatus employed in the application of one or more colors.

Briefly stated, an important object of this invention is to provide simple means whereby one or more colored fluids may be sprayed from a single device to produce a mottled or variegated effect.

A further object is to provide a spraying device or air brush, as the same is known, and a simple means whereby the flow of fluid through the several nozzles may be simultaneously controlled by means of a single control member.

15 A further object is to provide simple means whereby the spray head may be detached and replaced by one of a different type or style without entirely dismantling the device and without the exercise of unusual skill.

Also, an important aim of this invention is to provide an apparatus of the character described which is of highly simplified construction, durable in use and cheap to manufacture.

Other objects and advantages will be apparent during the course of the following description:—

In the accompanying drawings forming a part of this application and in which like numerals are employed to designate like parts throughout the same,

Figure 1 is a plan view of the improved spray apparatus.

35 Figure 2 is a vertical longitudinal sectional view through the same.

Figure 3 is a horizontal sectional view through the improved spray apparatus.

Figure 4 is a front end elevation of the apparatus illustrating the spray head.

Figure 5 is a rear end elevation of the improved applicator.

In the drawings, wherein for the purpose of illustration is shown a preferred embodiment of the invention, the numeral 5 designates a base or body plate to which an elongated handle and housing 6 is connected by means of fastening devices 7 in the nature of screw bolts or the like. Particular attention is directed to Figure 2 which illustrates that the top of the combined housing and handle is detachable to facilitate the original assembly of the apparatus and the periodical cleaning of the same.

55 A plurality of fluid conducting flexible hose sections 9 are extended through the

housing 6 and extend from suitable sources of supply. In this connection it might be stated that the several hose sections 9 have connection with containers for different colored fluids so that the fluids are all discharged simultaneously from the forward end of the device to produce a more or less mottled effect on the surface to be coated.

Particular attention is directed to the fact that a saddle 11 is extended transversely of the handle and housing 6 and has its somewhat narrowed upper edge positioned for engagement with the flexible hose sections 9 whereby to simultaneously cut off the supply of different colored fluids. The saddle is provided with a pair of upwardly directed attaching links 12 having connection with a spring 14 secured as indicated at 15 to the upper side of the combined handle and 75 protecting housing 6. When the leaf spring 14 is released it swings the saddle 11 upwardly to cut off the movement of the fluid and when the operator depresses the leaf spring 14 by his thumb, or otherwise, the 80 saddle 11 is lowered to allow the several fluids to be discharged from the apparatus or to the surface to be coated.

The forward ends of the hose sections 9 extend beyond the combined handle and 85 housing 6 and have connection with the shanks 16 of tapered nozzles 17, the said shanks 16 being extended through the head 18. The head 18 is in the nature of a rectangle having its front wall provided with a 90 plurality of tapered openings 19 to receive the nozzles 17 and the nozzles 17 may be tightened in these tapered openings by advancing the shank 16. Figure 2 plainly 95 illustrates that the rear portions of the shanks 16 are somewhat large and are externally threaded as indicated at 20 for threading engagement with the rear end walls of the head 18. Thus by an adjustment of the shanks 16 the nozzles 19 may be 100 tightened or loosened. The nozzles 19 are surrounded by air discharge vents 23 which communicate with the air chamber 24 so that a plurality of blasted air jets are directed from the front side of the head to create a 105 suction at the nozzles 17 whereby to draw the colored fluid through the hose sections 9 and into contact with the surface to be coated.

Figure 2 plainly illustrates that an air conducting pipe 25 is connected as indicated 110 at 26 to the air chamber 24 and this air pipe, which is provided with a valve 27, may ex-

tend from an air compressor, air tanks or the like.

It will be seen that the head 18 is detachably held in place by fastening devices 30 5 of any type so that the head and the nozzle carried thereby can be quickly replaced by a head of another size, so that the device may be readily modified for use in connection with various kinds of work. Also the front 10 wall of the head 18 is detachable so that access may be gained to the interior of the chamber for the purpose of detaching the nozzle 17 or for cleaning purposes.

With reference to the foregoing description 15 taken in connection with the accompanying drawings, it will be seen that one or a plurality of fluids may be sprayed from a single device for applying one or a plurality of colors to a surface to be coated.

20 The improved spraying device may be conveniently taken apart for the purpose of cleaning and reassembled all without the exercise of unusual skill.

Particular attention is directed to the fact 25 that the flow of the liquid through the various hose sections is controlled by means of a separate valve not shown so that the quantity of fluids discharged from one nozzle compared with the quantity of fluids discharged from another nozzle can be varied by 30 the operator.

Having thus fully described my invention what I claim as new is:—

1. In a spray apparatus a housing, a plurality of flexible conduits extending through 35 said housing, a movable member in said housing and supporting said conduits therein, and manually releasable tension means on said housing and in operative connection with said movable supporting member to 40 maintain said conduits closed by compression between said member and a portion of the housing.

2. In a spray apparatus a housing, a plurality of flexible conduits extending through 45 said housing, means for supporting said conduits in said housing in clamped and compressed position against a wall thereof, and spring means on said housing compressible to move said conduit supporting means to 50 release said conduits from clamped and compressed position.

3. In a spray apparatus a housing, a plurality of flexible conduits extending through 55 said housing, a saddle in said housing and supporting said conduits, a spring clip attached externally to said housing and manually compressible thereagainst, and links movable through said housing in connection with said clip and saddle whereby in 60 normal position of said clip said conduits are compressed between said saddle and a wall of the housing.

In testimony whereof I affix my signature.

CARADOC L. JONES.
